UNITED STATES PATENT OFFICE

EMIL GATHMANN, OF BALTIMORE, MARYLAND

INGOT MOLD

Application filed October 4, 1930. Serial No. 486,463.

This invention relates to apparatus for stripping ingots from ingot molds and more particularly to an improved apparatus for stripping ingots from molds having chambers larger in cross section at the top than at the bottom, such, for example, as the kind of mold now well known in the art as the Gathmann big-end-up mold.

In the commercial production of metal ingots it is the usual practice to place the molds into which a "heat" is to be poured on cars and then to fill or teem the molds with molten metal in the vicinity of the melting furnace. After the molds have been teemed, the cars with the molds thereon are moved to another part of the plant in which the ingots, having by this time solidified, are "stripped" or removed from the molds and then placed in a soaking pit for equalizing and, in some cases, raising the temperature of the ingot metal preparatory to subsequent working of the ingot.

Steel ingots are produced from either fully de-oxidized, semi-deoxidized, or "open" steel in accordance with the requirements of the product to be made or the practice of the particular plant or both. The best ingots obtainable from each of these kinds of steel are those cast in big-end-up molds. Ingots cast in such molds from fully deoxidized steel are generally provided with shrink head portions which are confined within hot tops of refractory material while the ingots are solidifying. After such an ingot has solidified, the hot-top may be broken away and the shrink head portion of the ingot then gripped by suitable tongs or the like and the entire ingot lifted from the mold while the latter is clamped down or otherwise held stationary. Before lifting such ingots from their molds in this way it is usually necessary to first loosen the ingot to facilitate its withdrawal. Ingots cast in big-end-up molds from semi-deoxidized or from "open" steel are normally not provided with a shrink head portion so that, after such an ingot has been cast, no part of the ingot projects above the mold proper and it is therefore not possible to merely grip the ingot and lift it from the mold as is the case with a big-end-up ingot having a shrink head portion.

Prior to the present invention, the practice most generally used in stripping ingots, cast without a shrink head portion, from big-end-up molds has been to "up-end" or invert the mold and contained ingot, then to loosen the ingot from the mold when necessary as by jarring the latter, and then to lift the inverted mold off the ingot, the latter remaining on the stool, table, or floor upon which it was placed when inverted. This "up-ending" practice heretofore generally resorted to necessarily results in much delay and high cost of handling of the ingot so that the big-end-up ingot has not heretofore been produced from semi-deoxidized or from "open" steel commercially in any considerable tonnage despite the fact that, as stated above, the best ingots obtainable from these kinds of steel are those produced in big-end-up molds. In my United States Patents 1,059,667 and 1,059,668, issued April 22, 1913, I have disclosed methods of and apparatus for stripping ingots cast without shrink head portions in big-end-up molds without inverting or up-ending the molds. The apparatus shown in the patents referred to may be used for example for stripping ingots from molds provided with bottom closures such as are shown in my prior Patent 1,660,037 of February 21, 1928. The present invention, however, relates to ingot molds provided with bottom closures which are adapted particularly for use in connection with improved stripping apparatus such as is disclosed in the present application. Although my improved molds for closures are especially useful in facilitating the stripping of ingots cast without shrink head portions, they may also be used to advantage for ingots cast with a shrink head portion for reasons to be hereinafter pointed out.

The primary object of my invention is to provide an improved mold construction for facilitating stripping a big-end-up ingot. In accordance with my invention, I employ big-end-up molds of the kind having a bottom opening which is closed by a novel closure device. Preferably the molds used are

each provided with a double closure means comprising a plug of refractory material, and a metal plate positioned in the mold bottom opening and out of contact with the refractory plug. Prior to teeming a jag of molds, I position one or more molds on a support which is preferably a car readily movable from the teeming place to the stripping location. This car or support is provided with a vertically reciprocable stripper rod arranged above or adapted to be positioned above a device for raising the stripper rod preferably comprising a cylinder having a fluid pressure actuated ram adapted to engage and lift the stripper rod. I so construct the stripper rod that its upper end is of somewhat smaller diameter than the opening in the bottom of the mold and so that it will project somewhat above the top surface of the support when the rod is in inactive or normal position. This projecting upper end of the stripper rod may be readily seen through the mold bottom opening when the mold is being positioned on the car prior to teeming, and thus serves advantageously as a means for accurately centering the mold with respect to the stripping rod. When one or more molds have been positioned upon the car in this way, their bottom openings are closed, preferably by means of the double closure referred to above. The molds are then teemed and moved to the stripping location, in which the supporting car is positioned over the ram which is then operated to raise the stripper rod and ingot until the upper end of the ingot is projected somewhat above the mold top. If desired, the upper end portion of the ingot may be then gripped by tongs and the ingot completely withdrawn from the mold, or, if it is desired to move the molds and contained ingots to still another location before completely removing the ingots, the stripper rods are locked in their raised positions and the car then moved to the desired location where the final stripping operation is performed.

A practical embodiment is illustrated in the accompanying drawings, in which:

Figure 1 is a diagrammatic view partly in section and partly in elevation of a part of a steel plant, and illustrating the use of my apparatus in practice;

Figure 2 is a vertical sectional view of an ingot mold and apparatus embodying my invention, some parts being shown in elevation;

Figure 3 is a view similar to Figure 2 with certain of the parts being shown in different positions from the positions shown in Figure 2;

Figure 4 is a fragmentary view in side elevation of the mold and apparatus shown in Figures 2 and 3; and

Figure 5 is a fragmentary horizontal sectional view taken on the line 5—5 of Figure 2.

The molds employed in carrying out my

invention may be of any suitable big-end-up kind having bottom openings, but are preferably of the kind known in the art as the Gathmann big-end-up mold. The accompanying drawings illustrate a Gathmann big-end-up mold A positioned on a support or transfer car B arranged to run on tracks C—C by means of which the mold may be readily transported from the teeming location near the melting furnace to the stripping location near the soaking pit. Although only one mold is shown on the car B, it will be understood that in practice any number of molds within reasonable limit may be placed on a single car.

The mold A is necked in at its bottom as at 1, and the bottom of the mold is formed with an opening comprising a relatively wide, tapered upper portion 2 and a relatively narrow bottom portion 3 arranged concentrically with respect to the upper portion 2. A horizontal peripheral seat 4 intervenes between the upper and lower portions of the opening and is adapted to support a metal closure plate 5. A closure plug 6 of refractory material is shown positioned with its periphery in contact with the tapered portion 2 of the mold bottom opening, and with its bottom surfaces disposed above and out of contact with the plate 5. The plug 6 and the plate 5 together constitute a double closure for the mold bottom opening so that any leakage of molten metal past the refractory plug resulting from its being slightly damaged during its insertion in the opening will be arrested by the plate 5 and no damage will occur.

The car B is provided with an opening 7 in which a stripper rod 8 is mounted for vertical sliding movements, and preferably the car is provided with a downwardly extending bearing sleeve 9 which serves to guide the stripper rod and to prevent binding of the latter. The sleeve 9 is provided with lugs 24 projecting laterally from it. It is desirable that the aforementioned parts be of rugged, inexpensive construction and for this reason both the car top and the stripper rod are of cast metal, the opening 7 in the car and the rod being unmachined and used as cast. For this reason considerable clearance is provided between the rod and opening to assure free working movement.

The stripper rod is provided at its upper end with an enlarged head 10, the lower face of which is tapered inwardly and downwardly as at 11 for engagement with a tapered seat 12 formed in the top of the car at the upper end of the opening 7. It will be observed that when the stripper rod is in its normal inactive position as shown in Figure 2 the rod will be supported by the engagement of the head with the seat 12.

In order to facilitate the centering of the mold with respect to the stripper rod, I so

arrange the head 10 that it will extend above the car top when supported on the seat 12 and I make the diameter of the head considerably less than the diameter of the lower portion 3 of the mold bottom opening. When it is desired to position a mold on the car preparatory to teeming, the mold is lifted by an overhead crane and then lowered on the car in such a way that the mold bottom opening will be disposed substantially concentrically with the stripper rod head, the latter serving as a guide for properly locating the mold.

After the mold has been thus positioned on the car the closures 5 and 6 are then positioned in the mold bottom opening and the mold teemed. It will be noted that, when the closures 5 and 6 are in place, the plug 6 is disposed above and out of contact with the plate 5, while the latter is disposed above and out of contact with the stripper rod head. This arrangement assures proper seating of the closures and effective sealing of the mold. By making the closures separate from the stripper rod no trouble will be encountered because of the sticking of the rod to the ingot. The car is then moved to the stripping station and positioned with the stripper rod disposed directly above a hydraulic ram 13 mounted for vertical movements in a hydraulic cylinder 14 which is preferably set in the floor.

It is necessary that, during the stripping operation, the mold and car be held against vertical movement. For this purpose I secure the mold to the car by means of a pair of hooks H—H each having an eye 15 adapted to receive one of the usual lugs 16—16 at the bottom of the mold, and a nose 17 adapted to project into a recess 18 formed in the side of the car. The car is in turn held against vertical movement by means of horizontal lugs 19 which project outwardly from each side of the car and each of which, when the car is in position for stripping, is disposed below the overhanging portion 20 of a bracket 21 anchored to the floor. Although only one such lug and bracket is shown on each side of the car, I prefer in practice to employ a plurality of spaced lugs and brackets on each side, since this arrangement provides a more stable anchorage for the car and mold.

When the mold and car have been thus anchored the ram 13 is caused to be moved up by the action of fluid under pressure supplied to the cylinder 14 from a source not shown. During the upward movement of the stripper rod, its head will engage the plate 5 and further movement will raise the ingot until the upper end portion thereof is extended above the top of the mold as shown in Figure 3. The upper end portion of the ingot will thus be accessible for being gripped by tongs T as shown in Figure 1.

In many cases it will be desirable to move

the mold and ingot from the location of the ram to another part of the plant before completing the withdrawal of the ingot by means of tongs. I accordingly provide means for locking the stripper rod in its raised position after the ram 13 has been retracted. In the illustrated embodiment of the invention, I have provided a latch 22 pivoted as at 23 to two lugs 24 projecting laterally from the sleeve 9 forming part of the car (see Figure 5). This latch is adapted to ride in a longitudinal slot 25 in the stripper rod and to seat in a recess 26 at the lower end of the slot when the rod has been raised. A handle 27 extending through an opening 28 in the side of the car and being pivoted to the latch as at 29 provides for the convenient disengagement of the latter from its cooperating recess 26.

In operation, when the rod and ingot have been raised in the manner described, the latch will automatically seat in the recess 26 and will thereby retain the rod and ingot in raised position, permitting lowering of the ram without lowering of the ingot. The car with the mold and ingot thereon may be then moved to the desired location, such for instance as to a soaking pit 30 as shown in Figure 1. The upper end of the ingot may then be conveniently gripped by the tongs T carried by an overhead travelling crane 31 and the ingot removed from the mold and placed in the soaking pit in the usual manner. The latch 22 will then be moved out of the recess 26 by means of the handle 27 and the stripper rod will drop to its normal position wherein the head 10 is disposed to serve as a guide for the centering of another mold on the car.

The crane and associated apparatus for lifting the ingot completely from the mold may be of any suitable construction but may advantageously include a lifting connection between the crane and the tongs comprising twin interlocking chains 32 and 33 of the kind shown and described in U. S. Patent 804,243 issued to John F. Meigs and Robert P. Stout November 14, 1905. The arrangement of these chains is such as to provide a substantially rigid suspension for the ingot, which will not permit swinging of the latter when being moved over the soaking pit.

The foregoing is a description of the procedure followed in stripping big-end-up ingots having no shrink head portion, from big-end-up molds. In stripping an ingot which is provided with a shrink head portion, the ram 13 is preferably moved upwardly only sufficiently to loosen the ingot from its initial contact with the mold walls, and the stripper rod will then be permitted to return to its normal position, i. e., with the head 10 seated on the car top. The shrink head portion of such an ingot as cast projects above the mold top and it is therefore usually not necessary to raise the body of the ingot above

the mold, since the tongs may readily engage the shrink head portion. However, my apparatus can be used to considerable advantage in the stripping of ingots of this class, since the initial slight lifting of an ingot overcomes any sticking relation between the ingot and mold and thus renders subsequent lifting of the ingot with tongs more easy.

Although means for stripping Gathmann big-end-up ingots cast with a shrink head portion are well known, I believe the present invention to provide the first efficient method and apparatus for efficiently loosening, raising, and locking in raised position within the mold a big-end-up ingot so that its upper portion may be gripped by tongs at a location remote from the apparatus for effecting the upward movement of the ingot.

My improved apparatus is thus applicable to the stripping of both kinds of big-end-up ingots, namely, big-end-up ingots cast with a shrink head, and those cast without a shrink head. Generally speaking, the method consists in supporting a mold with the bottom opening thereof disposed in substantially axial alignment with a stripper rod, sealing the mold bottom opening by means of a closure device, and preferably by means of a refractory plug positioned in said opening and a plate also positioned therein but below and out of contact with the plug and also out of contact with the stripper rod, casting the ingot, raising the stripper rod to move the ingot upwardly, and then gripping the upper end portion of the ingot and completely withdrawing it from the mold.

My improved molds are capable of use in connection with apparatus which is simple and of such arrangement that the various parts may be of the rugged construction necessary in casting plant practice. A jag of molds as set up in commercial production of ingots frequently consists of thirty to forty molds and heretofore, in commercial practice, it has been necessary to provide thirty to forty lifting rams for stripping the ingots of each jag, in other words, one ram for each mold. The arrangement of my apparatus and the carrying out of my invention are such that only one ram need be provided for raising the stripping rods and ingots of an entire jag, although several rams may be set up together as a unit when it is desired to attain greater speed in the stripping operation.

Heretofore, because of the high cost of stripping big-end-up ingots cast without a shrink head, few ingots of this kind have been cast on cars. By means of my invention such ingots may be stripped rapidly and cheaply, and the field for the use of the big-end-up mold, and consequently the field for the production of good quality steel, is thus greatly broadened.

I claim:

1. In an ingot mold of the kind provided

with a bottom opening through which a stripper device is adapted to be moved for stripping a contained ingot partially from the mold, the combination of a primary closure plug seated in said opening, and a secondary closure comprising a plate also seated in said opening below and out of contact with said primary closure plug, said plate being disposed entirely within said opening and not projecting below the bottom thereof. 70

2. In an ingot mold of the kind provided with a bottom opening through which a stripper device is adapted to be moved for stripping a contained ingot partially from the mold, the combination of a refractory primary closure plug seated in said opening, and a secondary closure comprising a metal plate also seated in said opening below and out of contact with said primary closure plug, said plate being disposed entirely within said opening and not projecting below the bottom thereof. 80

3. In an ingot mold of the kind provided with a tapered bottom opening smaller at the bottom than the top thereof and through which a stripper device is adapted to be moved for stripping a contained ingot partially from the mold, the combination of a primary closure plug seated in said opening with its periphery engaging the tapered walls of said opening, and a secondary closure comprising a plate also seated in said opening below and out of contact with said primary closure plug, said plate being disposed within said opening and above the bottom of said mold. 90

4. In an ingot mold of the kind provided with a bottom opening through which a stripper device is adapted to be moved for stripping a contained ingot partially from the mold, the combination of a horizontal seat formed in the wall of said opening intermediate the top and bottom of the latter, a primary closure plug seated in said opening above said seat, and a secondary closure comprising a plate supported on said seat within said opening and below and out of contact with said primary closure plug. 105

In testimony whereof, I have hereunto subscribed my name.

EMIL GATHMANN.
